[57] CLAIM

The ornamental design for a jump rope, as shown and described.

DESCRIPTION

FIG. 1 is a front elevational view of a jump rope showing my new design;

FIG. 2 is a side elevational view thereof, the side opposite being substantially identical; and,

FIG. 3 is a front perspective view of the handle and adjacent members shown on an enlarged scale.

FIG. 1

FIG. 2

FIG. 3
